ATTORNEY

UNITED STATES PATENT OFFICE.

LEONARD FRANZEN, OF BROOKLYN, NEW YORK, ASSIGNOR TO VIKING TOOL & MACHINE CO., INC., A CORPORATION OF NEW YORK.

ADVERTISING DISPLAY RACK.

Application filed January 6, 1925. Serial No. 795.

My invention relates to advertising display racks of the type wherein a plurality of shelves are hung in a revolving cage and travel with it, being held at a pre-determined angle to the vertical and successively presenting the merchandise on the shelves to the observers. One object of my invention is the elimination of the shaft on which such structures usually revolve, substituting a cage which may be lifted from the driving mechanism whenever desired. Another object is the simplification and cheapening of the mechanism to reduce the cost of the device, to provide simple, but effective, driving mechanism and the provision of simple means for holding the shelves at a pre-determined angle to the vertical.

In the drawing Fig. 1 is a side view of a rack embodying my invention; Fig. 2 a top, 20 sectional view of the structure of Fig. 1, on the line 2—2 thereof; Fig. 3 a sectional view of the structure of Fig. 4 taken on the line 3—3 of Fig. 4; and Fig. 4 an end view of the lower portion of the device.

25 The base structure comprises four corner posts 1, 2, 3 and 4, connected by end rails 5 and side rails 6.

Flanged wheels 7 and 8 are journaled on the forward posts 2 and 3. A shaft 9 is 20 journaled in the posts 1 and 4 and has flanged wheels 10 and 11, alining with the forward wheels 7 and 8, secured thereto. The frame or base carries a small motor 12 which drives a belt 13 to revolve a pulley 14, also mounted on the frame, which pulley is secured to a worm shaft 15. The worm engages a worm wheel 16 secured to the shaft 9 so that the motor causes the flanged wheels 10 and 11 to slowly 35 revolve.

The cage carrying the display shelves consists of two rings 17 and 18, connected by cross rods 19, 19, etc., and spaced apart so that the rings will ride on the flanged wheels 7, 8, 10 and 11. Each shelf 20 has a pair of bearing lugs 21, 21 on its under side 45 which lugs are notched to engage a cross rod 19. Stops 22, 22 are fastened to each rod to bear against the lugs on the shelf

to prevent endwise travel of the shelf 50 thereon.

To maintain each shelf at a pre-determined angle to the vertical an arm 23 is secured thereto on the under side, near one end, which arm carries a balance weight 55 24 which may be locked in any position to fix the angle at which the shelf will stand during the rotation of the cage.

In use the cage is set on the flanged 60 wheels and the shelves adjusted to the desired angle. The goods are placed on the shelves and upon starting the motor the flanged wheels 10 and 11 revolve driving the cage by friction and causing it to slowly revolve and successively display the goods 65 on the shelves. The forward wheels 7 and 8 are idlers and carry and guide the rings making up the cage.

If desired the base and driving mechanism may be concealed so that the observer 70 cannot discern how the cage is revolved thereby adding to the advertising value of the device.

I claim:—

1. An advertising display rack comprising 75 a base frame, a plurality of flanged wheels thereon, means for rotating certain of said wheels, a cage consisting of a pair of spokeless rings and cross rods connecting said rings resting on the flanged wheels and 80 adapted to be rotated thereby, shelves carried by said cage and means for holding said shelves at a predetermined angle to the vertical during rotation of the cage.

2. An advertising display rack comprising 85 a base frame, a plurality of flanged wheels thereon, means for rotating certain of said wheels, a cage consisting of a pair of spokeless rings, cross rods connecting said rings, said rings resting on the flanged wheels 90 and adapted to be rotated thereby, a shelf, a pair of notched lugs on the under side thereof engaging a cross rod, an arm secured to the under side of the shelf and a counter-weight on said arm.

In testimony whereof I have affixed my signature.

LEONARD FRANZEN.
